(57) **CLAIM**

The ornamental design for merchandising display rack, as shown and described.

DESCRIPTION

This application is related to co-pending U.S. design patent application Ser. No. 29/248,717 filed on Aug. 30, 2006 to the instant inventor.

FIG. 1 is a top view of a merchandising display rack showing my new design;

FIG. 2 is a frontal elevational view thereof;

FIG. 3 is side view thereof;

FIG. 4 is a bottom view thereof; and,

FIG. 5 is a perspective view.

The broken lines are for the illustrative purposes only and form no part of the claimed design.
